Isaac Doolittle, Brimington Vermont

Letter's Patent

The schedule referred to in these Letters Patent and making part of the same, containing a description in the words of the said Isaac Doolittle himself of his improvement in the machine called the American Watch, or Domestic Calendar.

To all persons to whom these presents shall come, Isaac Doolittle of Brimington, in the County of Brimington State of Vermont, sends greeting. Be it known that the said Isaac Doolittle has invented, constructed, made & applied to use a most useful machine called the American Watch, or Domestic Calendar, specifically in the words following, viz: This machine consists in a square or oblong frame of any convenient height, composed of four posts connected together transversely by four bars; the two front posts are longer posterior and higher than those in the rear; on this frame near the front posts, west two eyefaces, at a small distance apart, their axis being parallel to each other, & in the same horizontal plane, having plain cylinders intercalated in the frame. On a movable frame the ends of which are introduced into two mortises in the upper part of the front posts, while the other extremities left to describe an arc of a circle in the vertical plane about the pins which retain them in the mortises, are situated at such distance from the fulcrums as to bring the axis when the movable frame is horizontal directly over the middle of the space which separates the two cylinders above named, is placed the axis of a thin cylinder parallel to the two first, & on this cylinder the axis of which extends far enough eastward to receive a hand, & to admit of its being turned without touching the frame, is placed parallel to the other cylinders, resting on the two first, & is forth cylinder is covered with a cover of which being loose a circular frame or lid

from the cylinder; and this cloth developed, resting on one of the lower cylinders, is placed the use of the article to be smoothed, folded and to the proper width; by turning the hand in the proper direction the article is unfolded around the fourth cylinder, when a sufficient quantity for one operation, is then wound on the fourth cylinder in the movable frame is lowered to come in contact with it and a proper degree of pressure applied by means of a bar which connects the extremity of the movable frame, with a pole on which is placed the foot of the operator. Through this pressure the cloth cylinder is turned for a short time, in the same direction as the winding on the frame. The friction of this cylinder causes the others to revolve in the contrary direction, and the result is not, as is usually to moist the cloth submitted to the operation, but to give them a beautiful lustre. Since to be smoothed by this machine should be smoothed much less, than for smoothing by the common method I have not come to give dimensions because these may be varied at pleasure without altering the principle of the machine; the same may also be said of the materials of which it is constructed.

I do not claim as new any single or detached part of this machine, but I do claim as new the application of this combination of parts to the above use. In testimony that the above is a true specification of my said machine as above described, I have hereunto set my hand this 15th day of March, in the year of our Lord one thousand eight hundred and sixty two.
